UNITED STATES PATENT OFFICE.

EDWARD J. HART, OF PHILADELPHIA, PENNSYLVANIA.

UNDERFEED STOKER.

Application filed October 19, 1921. Serial No. 508,648.

To all whom it may concern:

Be it known that I, EDWARD J. HART, a citizen of the United States, residing at Philadelphia, in the county of Philadelphia and State of Pennsylvania, have invented new and useful Improvements in an Underfeed Stoker, of which the following is a specification.

My invention relates to new and useful improvements in underfeed stokers, and has for its object to provide a plurality of pushing heads located in spaced relation to each other along one or more edges of the grate, as a whole, for positively forcing the fuel over the grate longitudinally of the grate bars.

Another object of this invention is to construct the pushing heads separate from the grate bars and provide means to actuate them for forcing the fuel over the grate bars.

Another object of the invention is to produce a pushing head with an extension to be also used as a pusher where extra long grate bars are utilized.

A still further object of the invention is to provide a unique means for actuating the pushing heads and other coacting movable elements from the mechanism propelling the fuel injecting ram and fuel pushers in the retort.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:—

Fig. 1, is a fragmentary plan view of the interior of a furnace embodying my invention and illustrating the relation thereto, of the feeding mechanism and hopper, the latter being on the exterior of the furnace.

Fig. 2, is an enlarged sectional view approximately on the line 2—2 of Fig. 1.

Fig. 3, is an enlarged transverse sectional view of the interior constructions at approximately the line 3—3 of Fig. 1, some of the parts being left in elevation.

Fig. 4, is a fragmentary detail view similar to Fig. 3 illustrating the construction of the dumping grate elements.

Fig. 5, is a fragmentary view illustrating a pushing head with an extension, the stationary imperforate grate bar being shown in section.

Fig. 6, is a fragmentary horizontal sectional view through the partitions or walls of the air box above the dampers to illustrate the means of operating said dampers.

Fig. 7, is an enlarged fragmentary sectional view of the valve mechanism controlling the movable elements of the stoker.

Fig. 8, is a plan view of a portion thereof illustrating its relation to the valve actuating mechanism.

Fig. 9, is an enlarged fragmentary plan view of the adjustable means for transmitting motion from the pusher to the connecting rod of the rocking bars;

Fig. 10, is a front elevation thereof with the pusher removed while parts of the grate bars and retort and opposite pushing heads are shown to illustrate the relation of the different elements;

Fig. 11 is a fragmentary view partly in elevation and partly in section to show the relation between the valve mechanism and the means by which motion is transmitted to the different movable parts.

In carrying out my invention as here embodied, 2 represents a furnace the walls of which may be of any suitable construction and within this furnace is located a longitudinal retort 3 preferably centrally arranged and located below the grate surface.

The retort 3 is located above an air box 4 which communicates with air chambers 5 by means of openings 6 which are controlled by the dampers or wind grates 7 arranged in pairs opposite each other and each of said dampers or wind gates is connected by a rod 8 with an oscillating member 9 suitably pivoted to a depending member connected with the retort. All of the oscillating members 9 are connected by an operating rod 10 whereby all of the oscillating members may be simultaneously actuated for opening or closing the wind gates. The operation of the wind gates will be obvious upon reference to Fig. 6. The air chambers 5 are directly below the grates consisting of the imperforate grate bars 11 and the perforate grate bars 12. As shown in Fig. 3 the perforate grate bars are movable longitudinally and rest upon the upper edges of the retort 3 and the outer partitions 13.

Each of the perforate grate bars 12 is con-

structed in the form of steps, each step having two side walls converging toward each other terminating in an apex and in these converging side walls are located the draught outlets 14; also each of these grates has a hollow head 15 through which the draught openings 16 are formed and between these perforate grate bars 12 are located the imperforate grate bars 11 the same having lugs 17 to engage on both sides of the outer partitions 13 on which the outer ends of the imperforate grate bars 11 rest. The inner ends of the grate bars 11 rest in the recesses 18 formed in the pushing heads 19. Each of said pushing heads has a pushing face or surface 20 above its respective grate bar and also has spaced lugs 21 which engage the web 22 of the rocker shaft 23 and likewise the perforate grate bars 12 are provided with spaced lugs 24 which also engage the web 22 of the rocker shaft 23.

As there are two sets of grate bars one on each side of the retort two rocker shafts are shown and all of the grate bars are inclined towards their outer ends, as plainly shown in Fig. 3.

From the foregoing description it will be noted that as the rocker shafts are oscillated the perforate grate bars 12 and the pushing heads 19 will be reciprocated so as to gradually force the fire bed fuel outwardly along the grate bars and during this time the desired amount of air is permitted to flow through the perforate grate bars and through the draught openings in the hollow heads formed with said grate bars.

As the fire bed is moved forward it will finally be moved on to the sectional dump grates 25 one of which is located at each side of the furnace below the lowermost ends of the grate bars and all of the sections 26 of each dump grate are fastened together by means of an angle iron 27 or its equivalent secured to the sections by bolts 28, said sections also being fastened to a dumping bar 29.

The dumping bar is preferably rectangular in cross section, as shown in Fig. 4, while each section of the dumping grate is formed of two parts securely held about a dumping bar by means of a bolt 30.

The dumping grates are located above the ash pits 31 to which lead air conduits 32 from the air box 4, said conduits being controlled by dampers 33, here shown as butterfly valves, actuated in any suitable well known manner so that should any unburned fuel happen to reach the dump grates a sufficient amount of air may be supplied thereto to cause the same to be entirely burned before entering the ash pits.

The fuel is fed from a hopper 34 located, on the outside of the furnace, by a ram 35, operative in the throat 36, into the retort 3

along which it is moved by the pushers 37. The ram as shown is a hollow box like member formed of two interlocking parts held together by a pin 36 or its equivalent and this ram is connected to an extension 37 of the slide 38 attached to the piston rod 39 of the piston 40 sliding in the cylinder 41. To the slide 38 is attached the pusher rod 42 to which all of the pushers 37 are fixed.

The movements of the piston 40 cause the pushers 37 and the ram 35 to be reciprocated for moving the fuel so that the same will gradually pile up within the retort and run over on to the grate bars where it will be moved forward by the pushing heads and the reciprocating grate bars 12 and in order to prevent the fuel becoming choked in the smaller lower end of the hopper I provide an agitator 43 which consists of two bars 44, 45 pivoted to each other as at 46 with one also pivoted to the ram as at 47 and the other to some suitable part of the hopper as at 48 the movements of the ram causing the parts of the agitator to be drawn across the mouth of the hopper and at times causing it to be moved partly out of and into said hopper thereby effectually loosening or breaking up any fuel which may have a tendency to clog in the smaller end of said hopper.

On the slide 38 is pivoted a yoke 49 by means of an integral trunnion 50 formed with said yoke and set in a suitable recess in the slide and one end of said yoke is recessed in a block 51 having threaded connection with an adjusting screw 52 swivelled in any suitable manner in the side walls or projections 53 formed with the slide 38 and said screw has means 54, here shown as a hand wheel, mounted thereon for revolving the screw to move the blocks 51 transversely of the slide whereby the pitch of the yoke is changed as desired.

Arranged to function within the yoke is a roller 55 on the trunnion 56 carried by the connecting rod 57, the ends of which are connected in any suitable well known manner to the rocker arms 58 carried by the rocker shafts 23.

From the foregoing it will be seen that as the slide 38 is reciprocated the yoke 49 will transmit motion to the connecting rod 57 and at right angles to the line of movement of the slide causing the rocker shafts to be oscillated for transmitting a reciprocating motion to the movable grate bars and pushing heads and the amount of this movement will be controlled by the pitch of the yoke which may be changed at the option of the operator, as will be obvious.

The movements of the piston 40 are controlled by the entrance of steam into one or the other end of the cylinder 41 depending upon the position of the piston in said cylinder, the steam in its passage to the cylinder from a suitable source of supply first enter-

ing the steam chest 59 through port 59' from where it will pass through one of the openings 60, 61 from said steam chest and through pipes 60' and 61' to the cylinder 5 and during the time the steam is entering one of said openings the exhaust steam will be leaving the other opening and pass through the exhaust 62 to the atmosphere.

These openings and exhaust port are controlled by a valve 63 which is slidably mounted upon a piston rod 64 between two tappets 65 and its piston rod is connected to a governor piston 66 mounted within the cylinder 67. As the governor piston is moved in one direction the piston rod will slide through the valve 63 without affecting the position thereof until said governor piston has almost completed its movement at which time one of the tappets 65 will engage the valve 63 thereby moving said valve to close that opening leading to the cylinder 41 which had been open, at the same time uncovering the other opening so as to change the direction of movement of the piston 40 as will be obvious.

The governor piston is controlled by a control valve 68 functioning within a valve housing 69 and having a valve stem 70 on which are mounted tappets 71 coacting with a pivoted reversing lever 72 actuated by the movements of the ram 35 in any suitable or well known manner but as here shown the means for actuating the reversing lever 72 includes a lever controlling rod 172 having one end fixed to the reversing lever 72 above the pivot point of the latter while the opposite end of said controlling rod runs in the inclined guide 173 on the side of the ram 35. The inward movement of the ram 35 will slide the guide 103 relative to the lever controlling rod 172 and therefore raise that end of the rod within the guide so that a swinging or rotary motion will be transmitted to the reversing lever 72 until its upper free end moves over and engages the tappet 71 nearest the valve housing 69, and thereby shift the controlling valve 68. Into the control valve housing leads an inlet port 73 having branches 74 leading therefrom to the valve chamber said branches being opened or closed by the movements of the control valve 68 which also controls the passageways 75, 76 leading from the valve chamber to the cylinder 67. The fluid entering the valve chamber through the inlet port 73 must be under pressure and although any suitable fluid may be used I have found that a free running oil has many advantages, some of which are its non-freezing and lubricating properties.

From the foregoing description it will be noted that the movements of the ram 35 will move the reversing lever 72 into contact with first one and then the other of the tappets 71 thereby moving the control valve 68 back

and forth within the valve housing for opening and closing the alternate branch ports leading from the inlet 73 and also alternately opening and closing the passageways 75, 76 so that the governor piston 66 will be actuated to move the valve 63 hereinbefore stated. The valve 68 is of such construction that when a communication is formed between the inlet 73 and the passageway 75 a communication is also formed between the passageway 76 and the exhaust 69', thus allowing the fluid which has moved the governor piston to flow into a suitable container and likewise when the fluid enters the port 76 the valve 68 will be in a position to permit the fluid in the cylinder 67 to pass through the port 75 into the exhaust.

The construction illustrated in Fig. 5 is particularly useful in conjunction with extra long grate bars and provides additional pushing means and in this form of the device the imperforate grate bar 11" is held in its set position by the lugs 17" engaging the outer partitions 13 and said imperforate grate bar is provided with a slot 78 intermediate its ends through which projects an extension 79 formed with the lower portion of the pushing head 19" having a pushing face 20" rising above the upper end of the imperforate grate bar, the said pushing head also having a recess or slot 18" for the reception of said upper end of the imperforate grate bar.

This pushing head is actuated in the same manner as the others herein described, it being provided with lugs 21" for coaction with the web 22 of the rocker shaft 23.

This form of the invention is preferably used in connection with the movable perforate grate bars 12 one of which is illustrated directly behind the imperforate grate bar and the movements of the pushing head will first advance the fuel of the fire bed along the upper portion of the grate bars as said fuel runs over the pushing heads and upper ends of the grate bars and at some point further down the grate bars it will be given another propelling movement by the extension 79 as the same is projected through the slot 78.

The gist of my invention is to provide pushing heads in conjunction with the grate bars of a stoker regardless of the particular construction of said grate bars and further to construct the pushing heads separate from said grate bars and therefore I do not wish to be limited to the exact details of construction as herein shown as these may be varied within the limits of the appended claims without departing from the spirit of my invention.

Having thus fully described my invention, what I claim as new and useful is:—

1. An underfeed stoker comprising, in combination, a retort, grate bars extending

laterally from said retort, alternate ones of said grate bars being movable longitudinally and the others stationary, and reciprocating pushing heads slidably mounted on the stationary grate bars.

2. An underfeed stoker comprising, in combination, a retort, grate bars extending laterally from said retort, alternate ones of said grate bars being movable longitudinally and the others having their outer ends anchored to hold them stationary and pushing heads slidably mounted on the retort and on the inner ends of the stationary grate bars, said pushing heads supporting said inner ends of the stationary grate bars.

3. An underfeed stoker comprising grate bars, pushing heads slidably mounted thereon, and means for reciprocating said pushing heads.

4. An underfeed stoker including grate bars and reciprocating pushing heads slidably mounted thereon.

5. In an underfeed stoker, a plurality of perforate grate bars, a plurality of stationary imperforate grate bars alternately located with respect to the perforate grate bars, and reciprocating pushing heads slidably mounted on the stationary grate bars.

6. In an underfeed stoker, a plurality of longitudinally movable grate bars, a plurality of stationary grate bars alternately located with respect to the movable grate bars, and reciprocating pushing heads slidably mounted on the stationary grate bars.

7. In an underfeed stoker, a plurality of movable grate bars, a plurality of stationary grate bars alternately located with respect to the movable grate bars, pushing heads slidably mounted on the stationary grate bars and having pushing faces projecting above and overlying the upper ends of the grate bars on which they are mounted, and means for reciprocating said pushing heads.

8. In an underfeed stoker, a plurality of movable grate bars, a plurality of stationary grate bars alternately located with respect

to the movable grate bars, pushing heads slidably mounted on the stationary grate bars and having pushing faces projecting above and overlying the upper ends of the grate bars on which they are mounted, and means for reciprocating the pushing heads and the movable grate bars in unison.

9. In an underfeed stoker, stationary grate bars and movable grate bars arranged in alternate relation, pushing heads slidably mounted on the stationary grate bars, and means to reciprocate said pushing heads and the movable grate bars.

10. An underfeed stoker including grate bars having slots therethrough intermediate their ends, pushing heads slidably mounted on the grate bars, extensions carried by said pushing heads and projecting into the slots through said grate bars, and means for reciprocating said pushing heads.

11. An underfeed stoker including a plurality of longitudinally movable perforate grate bars, a plurality of stationary imperforate grate bars alternately located with respect to the perforate grate bars and having slots therethrough intermediate their ends, pushing heads slidably mounted on the imperforate stationary grate bars, extensions carried by said pushing heads and projecting through the slots, and means for reciprocating the movable grate bars and said pushing heads.

12. An underfeed stoker comprising, in combination, a retort, grate bars located on both sides of said retort, alternate ones of said grate bars being movable longitudinally and the others stationary, pushing heads slidably mounted on the stationary grate bars at the retort ends, pushers in the retort, and a mechanism for reciprocating the retort pushers, the pushing heads and the movable grate bars.

In testimony whereof, I have hereunto affixed my signature.

EDWARD J. HART.
